UNITED STATES PATENT OFFICE.

UNO L. SUNDBLAD, OF NEW HAVEN, CONNECTICUT, ASSIGNOR OF ONE-HALF TO
CHARLES W. WELLS, OF NEW HAVEN, CONNECTICUT.

SELF-WINDING ELECTRIC CLOCK.

Application filed August 11, 1924. Serial No. 731,315.

To all whom it may concern:

Be it known that I, UNO L. SUNDBLAD, a citizen of the United States, residing at New Haven, in the county of New Haven 5 and State of Connecticut, have invented a new and useful Improvement in Self-Winding Electric Clocks; and I do hereby declare the following, when taken in connection with the accompanying drawings and 10 the characters of reference marked thereon, to be a full, clear, and exact description of the same, and which said drawings constitute part of this application, and represent, in—

15 Fig. 1 a face view of a self-winding electric clock constructed in accordance with my invention.

Fig. 2 a side view of the same.

Fig. 3 a detached, plan view, on an enlarged scale, of the spring-barrel, with its 20 slide and dog in their positions when the spring is wound.

Fig. 4 a similar view, showing the position of parts when the spring is unwound 25 and ready for re-winding.

Fig. 5 a broken, sectional view of the spring-barrel and adjacent parts.

This invention relates to improvement in self-winding electric clocks, and is an improvement on the device shown and described in Patent No. 1,143,664, granted to me June 22, 1915. The object of the invention is to simplify the electric contacts, whereby they are more direct, and, therefore, more positive in action, and the invention consists in the construction as hereinafter described and particularly recited in the claims.

In carrying out my invention, I employ 40 the usual clock-mechanism which need not be described other than to refer to the usual spring-barrel 10, which contains a spring 11, one end of which is fixed to the barrel 10 and the other to the main-spring arbor 12. 45 This spring-barrel is formed with an annular gear 13, meshing with a pinion 14 on a winding shaft 15 driven by an electric motor which will not be described other than to say that one side is 50 connected with a binding-post 16, with which one wire from a battery, not shown, is attached. The other side of the motor is connected by a wire 17 with a contact-disk or ring 18 mounted on a bridge 19 55 and insulated therefrom. A binding-post

20 for the second wire of the battery is connected with case 21 and through the case is grounded with the clock-movement. Mounted on the rear face of the spring-barrel is a slide 22 guided for movement 60 by a screw 23 passing through a clearance-slot 24. This slide carries an inwardly-projecting pin 25, which I will hereinafter refer to as the spring-pin, the pin extending through a clearance slot 26 in the barrel and entering between the outer convolutions of the spring 11. Pivottally mounted on the face of the slide is a dog 27 carrying a contact-pin 28 which extends into the plane of the disk 18. This dog has a locking-notch 29 in position to be engaged with the nose 30 of a spring-latch 31, and extending into the plane of the contact-pin 28 is a spring contact-arm 32 secured to the barrel, so as to have electrical contact therewith. Bearing upon one side of the barrel is a brush 33 carried by a bowed bar 34, the ends of which bear against case-pillars 35 and 36 and through them making electrical connection with the case. 70

Assuming the clock is to be wound, as indicated in Fig. 3 of the drawings, the spring-pin 25 is drawn toward the center of the barrel by a contraction of the convolutions of the spring, and in this position, the dog 27 is engaged by the latch 31, so as to hold the post 28 out of engagement with the disk 18. As the spring unwinds, the spring-pin 25 moves toward the outer wall of the spring-barrel, and when the spring is unwound, or nearly so, as shown in Fig. 4 of the drawings, the dog is turned out of engagement with the latch and swings so as to cause the contact-pin 28 to engage with the disk 18, and so close 95 the circuit through the motor, starting that in motion and turning the shaft 15 and gear 14, and hence turning the spring-barrel so as to re-wind the spring. When the contact-pin 28 engages with the disk 18, 100 the circuit passes through the contact-arm 32, through the barrel 13, and through the brush 33 and bowed bar 34 to the case. When the spring is wound, the dog turns on the slide until it is caught by the spring-latch, which then comes into position to hold the dog and move the contact-pin out of engagement with the disk 18. 105

It will thus be seen that the electric circuit is practically direct and does not pass 110

through the slide and other parts, as was necessary in my previous construction.

I claim:

1. In a self-winding electric clock, the combination with a clock-movement including a spring-barrel, of an electric motor, a contact-disk connected with one side of said motor, a slide mounted on said spring-barrel and carrying a spring-pin extending into the convolutions of the spring, a dog mounted on said slide and carrying a contact-pin extending into the plane of the contact-disk, means for holding said dog out of engagement with said disk, a contact-arm in the path of the said contact-pin, said arm connected with the barrel, and a brush in contact with said barrel and with said case.
2. In a self-winding electric clock, the combination with a clock-movement including a spring-barrel, and spring, of an elec-

tric motor, a disk insulated from the clock-movement and connected with one side of the motor, a slide mounted on said spring barrel and carrying a spring-pin extending into the convolutions of the spring, a dog pivotally connected with said slide and formed with a notch, a spring-latch adapted to engage with said notch, a contact-pin carried by said dog and extending into the plane of the said contact-disk, a spring contact-arm mounted on the barrel and extending into the path of the contact-pin, and a bowed bar in electrical connection with the clock-case and bearing upon the spring-barrel. 35

In testimony whereof, I have signed this specification in the presence of two subscribing witnesses.

UNO L. SUNDBLAD.
